LIGHTED CIGARETTE HOLDER

William S. Glance, White Haven, Pa.

Application May 22, 1951, Serial No. 227,724

3 Claims. (Cl. 131—174)

1

This invention relates to lighted cigarette holders and more particularly to a portable safety holder which can be carried in a pocket when not in use and will protect a lighted cigarette and prevent ignition of inflammable material by the cigarette.

It is among the objects of the invention to provide an improved safety holder for lighted cigarettes which will receive a lighted cigarette and hold it firmly in place with its lighted end completely enclosed in a receptacle or housing of noninflammable material; which provides a receptacle for cigarette ashes, cigarette butts and used matches; which can be conveniently carried in a pocket or handbag when not in use and can be supported on clothing, such as a belt, or on a fixed support while being used; which can be completely closed when not in use and is easy to clean; which can be ventilated to maintain a cigarette supported therein in lighted condition and to avoid excessive temperatures; and which is simple and durable in construction, economical to manufacture, and neat and attractive in appearance.

Other objects and advantages will become apparent from a consideration of the following description and the appended claims in conjunction with the accompanying drawing wherein:

Figure 1 is a perspective view of a cigarette holder illustrative of the invention;

Figure 2 is a longitudinal cross sectional view on the line 2—2 of Figure 1;

Figure 3 is a transverse cross sectional view on the line 3—3 of Figure 2; and

Figure 4 is a longitudinal cross sectional view on the line 4—4 of Figure 2.

With continued reference to the drawing, the holder comprises a hollow housing or receptacle, generally indicated at 10, having flat walls including a top wall 11, a bottom wall 12, side walls 13 and 14 and end walls 15 and 16. The walls of the housing are in the form of flat, rectangular plates of a suitable noninflammable material, such as metal or a suitable synthetic resin plastic.

The top wall 11 is provided intermediate its length with a ventilating opening 17 of rectangular shape and a cap 18 is hinged to the outer side of the top wall in position to cover the ventilating opening. This cap comprises a flat upper wall 19 of rectangular shape and a flange 20 extending perpendicularly from the upper wall marginally thereof, the flange being connected at one end of the cap to the top wall 11 by a hinge 21 located adjacent one end of the ventilating opening and being engaged at the other end of the cap by a

2

spring detent 22 secured to the top wall 11 and extending through the ventilating opening at the corresponding end of the latter and at the inner side of the cap flange. The upper wall 19 of the cap has a portion extending beyond the flange at the end of the cap remote from the hinge, as indicated at 23, to provide a finger grip for opening and closing the ventilating opening.

The end wall 16 is hinged at one end to the corresponding end of the bottom wall 12 by a hinge 24 and carries a spring latch or detent 25 engageable with a projection on the inner side of the top wall 11 at the corresponding end of the latter, so that this end of the receptacle can be opened to dump material, such as cigarette ashes, cigarette butts, and used matches from the receptacle and clean the receptacle. The end wall 16 projects above the top wall 11, as indicated at 26, to provide a finger grip for opening and closing this end of the receptacle.

The end wall 15 is provided near the top wall 11 with a cigarette receiving aperture 28 of circular shape and a shelf 29 of substantially semi-cylindrical shape is secured at one end to the inner side of the end wall 15 at the side of the aperture 28 remote from the top wall and projects inwardly of the receptacle from the end wall 15 substantially parallel to the top wall to support a cigarette inserted lighted end first through the aperture 28, as is particularly illustrated in Figure 2.

A leaf spring 30 is secured at one end to the under side of the top wall 11 at a location spaced outwardly from the end wall 15 and has at its other end a cigarette engaging formation 31 which is biased to engage the upper side portion of a cigarette horizontally disposed between the shelf 29 and the top wall 11 for engaging the cigarette after it has been inserted through the aperture 28 and firmly holding the same in position on the shelf 29.

The top wall 11 is provided adjacent the end wall 15 with a pin receiving aperture 32 and a pin 33 is secured at one end to the cigarette engaging portion 31 of the spring clip and extends through the aperture 32 in the top wall. At its outer end the pin is provided with a finger knob 34 providing a finger grip, so that the pin can be pulled outwardly to free the spring clip from a cigarette clamped between the spring clip and the shelf 29 and the pin is provided intermediate its length with a stop collar 35 which bears on the outer surface of the top wall to limit movement of the pin inwardly of the receptacle.

The end wall 15 is provided on its outer side

with formations 36 and 37 of channel shaped cross section extending one along each longitudinal edge thereof and providing grooves or guideways at the opposite sides of this end wall. A door 38 is slidably mounted in the formations 36 and 37 and has a length materially less than the length of the end wall 15. This door is slidable between a position in which it overlies and closes the cigarette receiving aperture 28 in the end wall 15 and a position in which it is disposed between this aperture and the bottom wall 12, a knob 39 being secured to this door and projecting outwardly therefrom to provide a finger grip for moving the door.

With this arrangement, when the end wall 16, 15 the cap 18 and the door 38 are in closed position, the receptacle is tightly closed so that cigarette ashes cannot be spilled therefrom. When it is desired to place a lighted cigarette in the holder, the door 38 is moved away from the cigarette receiving aperture 28, the pin 33 is pulled outwardly and the cigarette is inserted, lighted end first, through the aperture 28 and between the shelf 29 and the cigarette engaging portion 34 of the spring 33. The pin is then released and the spring firmly clamps the cigarette in position on the shelf. The cap 18 closing the ventilating opening 17 may now be periodically moved to open position, as illustrated in broken lines in Figure 2, to vent smoke and products of combustion from the interior of the receptacle and replenish the air supply therein to maintain the cigarette in lighted condition and prevent the receptacle from being overheated. Any ashes or sparks leaving the cigarette will fall into the receptacle where they cannot ignite any inflammable material adjacent the holder. When it is desired to remove the cigarette from the holder the pin 32 is raised to release the cigarette from the spring clamp 30 and the cigarette is then removed through the aperture 28.

A pair of spring clips 40 and 41 are secured each at one end to the side wall 14 of the receptacle adjacent the top wall 11 and one near each of the end walls. These spring clips extend along the side wall 14 substantially parallel to the end walls of the receptacle and have their free ends outwardly curved and bearing against the side wall near the bottom wall 12. These spring clips are used to support the holder on clothing, such as a belt or on the outside of a pocket. The holder may also be set on a supporting surface, such as a bench or table, or on the ground when it is used out of doors.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A cigarette holder comprising a closed receptacle having walls including a top wall and

a pair of end walls, said top wall having a ventilating opening and one of said end walls having a cigarette receiving opening therein, the other end wall being hinged to said receptacle and movable to an open position for cleaning the interior of the receptacle, a shelf secured at one end to the inner side of one end wall at the lower portion of said cigarette receiving aperture and extending from said one end wall inwardly of said receptacle adapted to support a cigarette inserted through said aperture, a spring clip secured to said top wall and having a cigarette engaging portion disposed between said shelf and said top wall adapted to resiliently clamp a cigarette in position on said shelf, a pin secured at one end to said cigarette engaging portion of said spring extending slidably through said top wall, and a cap hinged to said top wall and adapted to be positioned to cover said ventilating opening.

2. In a cigarette holder, a closed receptacle having side, top, bottom and end walls and having a cigarette receiving aperture in one end wall thereof, a shelf secured at one end to the inner side of said one end wall at the lower portion of said aperture, a spring secured to the lower portion of the top wall of said receptacle having a cigarette engaging portion disposed adjacent the upper portion of said aperture and in opposition to said shelf, and means connected to said cigarette engaging portion of said spring extending through the top wall of the receptacle for manually moving said cigarette engaging portion away from said shelf for the insertion of a cigarette therebetween.

3. A cigarette holder comprising a closed receptacle having side, top, bottom and end walls and having a cigarette receiving aperture in one end wall thereof, a shelf secured at one end to said one end wall at the lower portion of said aperture, a spring secured to the top wall of said receptacle wall having a cigarette engaging portion disposed adjacent the upper portion of said aperture and in opposition to said shelf, means connected to said cigarette engaging portion and extending through the top wall of the receptacle for manually moving said cigarette engaging portion away from said shelf for the insertion of a cigarette therebetween, one wall of the receptacle having a ventilating opening therein, and means hinged to said last-named one wall and movable into and out of closing relationship with said opening.
